SLIDE FASTENER MACHINE

Alfred Sonntag, Greenwich, Conn., assignor, by
mesne assignments, to Talon, Inc., a corpora-
tion of Pennsylvania

Application August 13, 1948, Serial No. 43,972

11 Claims. (Cl. 78—31)

1

This invention comprises improvements in or relating to machines for manufacturing sliding clasp fasteners.

It is an object of the invention to provide a machine for manufacturing sliding clasp fastener elements from strip material and applying them to stringer-tapes, which is capable of operating at high speed with a minimum of friction and of wearing parts.

In Patent No. 2,437,793, there is described a machine of this character, having a reciprocating head and a foundation block, which two parts carry punches and dies for forming and severing fastener elements and also serve to operate closing members for securing the fastener elements on to a stringer-tape, the reciprocating head being mounted in a slide and actuated by an eccentric drive. Any machine in which a reciprocable head is guided in a slide is liable to considerable friction and wear, both of which are accentuated under high speed operation.

In the manufacture of sliding clasp fasteners, not only does the head have to be reciprocated at very high speed for long periods of time but the very highest accuracy of movement is essential, on account of the smallness of the parts, and any play which may develop, even as little as $\frac{1}{1000}$ of an inch, is highly objectionable; indeed, the ordinary limit of accuracy in the manufacture of these parts is less than $\frac{1}{1000}$ of an inch.

The present invention comprises, in a machine for forming sliding clasp fastener parts, the employment of flexplates for transmitting forces, taking the place of the customary linkages and cranks for use in such transmission of power to the movably-mounted parts of the machine. In particular, the invention contemplates the employment of means, such as flexplates, for imparting the necessary power to a reciprocating fastener-forming head, wherein the direction of movement of the power-transmitting means is such as to reduce and even eliminate much of the lateral thrust derived from links and cranks.

In one important aspect, the invention comprises, in a machine particularly shown for forming sliding clasp fastener elements from strip material, but capable of use in other associations, a construction which includes a support, a reciprocable head and a foundation block (which latter two parts carry punches and dies for forming and severing fastener elements), flexplates which extend from the support to the head, with the flats of the flexplates in parallel planes, so that they guide the head and hold it against canting forces, and means for reciprocating the head.

2

"Flexplates" may be bars of spring material which usually are flat, or flattened along a portion of their length. This feature, however, is to introduce the factor that, at a portion of the member, the cross-section is reduced and so formed that, when placed in compression, it will flex. Thus, in the conversion of rotary to reciprocatory motion, where the reciprocatory motion is of slight degree, cams or eccentrics, the usual media of transmission may be substantially eliminated.

These flexplates are constructed to be springy, but to remain stiff enough to enable them to take a substantial end load without buckling. The flexplates are normally made of a single piece of material. They may be made otherwise, as, for instance, like a laminated spring. The effect of employing flexplates in a manner described is that they not only permit movement of the head and hold it so that its reciprocation continues indefinitely along the same line of approach to the work, but also, owing to the flats of the flexplates being located in different parallel planes, the head is held against canting forces, which is an essential for the purpose in view.

While the construction of the ram, and the associated dies and feeding mechanism for the strip and for securing the fastener elements to the stringer-tape, such as are described in the aforesaid Patent No. 2,437,793, are indicated as a part of this apparatus, according to the present invention, it is to be understood that alternative forms of punches and dies and feeding mechanism can be employed without departing from the present invention.

Preferably, the flexplates, as viewed in a direction at right-angles to the planes of their flats, are arranged to form a triangulated structure; thereby the rigidity of the support of the head against lateral forces is increased.

It is a further feature of the present invention that the means for reciprocating the head should include a driving member for lifting the head away from the foundation block, and preloading springs for returning it to execute its working stroke in producing the fastener elements, which preloading springs are accurately designed to compensate for the amount of pressure used in cutting and preforming the fasteners; in other words, the preloading spring can be preloaded for the exact number of pounds necessary to act and to form any particular fastener element.

Preferably the driving member consists of one or more ball or roller bearing eccentrics which carry eccentric straps connected to the head by

flexplates. In this way, in conjunction with the use of the spring referred to, "play" or lost motion in the drive is eliminated, and extremely high speeds of operation, without loss of accuracy in the movement, become possible.

Preferably the foundation block carries a bracket in the form of an arm which extends above the reciprocable head and carries feeding means for the stringer-tape, which bracket is pivotally mounted on the foundation block so that when the machine is stopped it can readily be swung out of the way. This permits very convenient access to the foundation block for the purpose of renewing or adjusting the punches and dies carried by the head and the block.

The following is a description by way of example of one construction of a machine in accordance with the invention.

In the accompanying drawings:

Figure 1 is a front elevation of the machine; 20

Figure 2 is a side elevation of the same;

Figure 3 is a section of a part of the mechanism upon the line 3—3 of Figure 2, looking in the direction of the arrows;

Figure 4 is a plan;

Figure 5 is a sectional view taken on line 5—5 of Fig. 4, and

Figure 6 is a view of an assembly frame forming part of the machine.

Referring to Figures 1 and 2, upon a horizontal steel baseplate 11 there are secured two channel-shaped uprights 12, 13, which are disposed with their flanges facing one another and are united at the top by a heavy steel block 14, which constitutes a foundation block for punch and die elements. The steel baseplate 11 is approximately square in plan, and is suspended at the four corners on bolts 15 which extend upwardly from it through bracket arms 16 overhanging the baseplate. The bracket arms are cast in one piece with floorplates 17, and above the bracket arms around the bolts are supporting springs 18 on the upper ends of which bear cup washers 19 threaded on the bolts 15 and limited by nuts 20. Thus the foundation plate is suspended on springs at each corner, and the springs are made strong enough to support the weight of the parts. They afford a flexible connection which tends to absorb vibrations which would otherwise be transmitted to the floor on which the machine stands.

On the baseplate there is mounted a driving motor 21, and beneath the foundation block 14 there are secured, on the opposite side of the standards from that on which the driving motor is located, two ball bearings 22, 23 for a driving shaft 24 for the machine. The driving shaft 24 passes through the ball bearings and carries on one end a flywheel 25 and a V-grooved pulley 26 for a driving-belt 27 from the motor.

Between the ball bearings the driving shaft 24 is machined slightly eccentric at two places 28, 29 and on these eccentric portions are mounted ball races 30, 31 which fit into eccentric straps 32, 33 (Figure 3).

Above the eccentric straps 32, 33 the foundation block is drilled through at 34, 35 and two flexplates 36, 37 having screwed ends 38, 39 are screwed into the two eccentric straps and pass upwardly through the drilled holes 34, 35 in the foundation block. The flexplates are machined to provide flattened portions 40, 41 which are sufficiently springy to allow the lateral movement called for by the eccentricity of the eccentric portions 28, 29 on which the ball races are mounted, the flattened portions moving within the afore-

said drilled holes. Above the foundation block the flexplates carry shanks which pass upwardly through a reciprocable head 44. Spacer washers 45, 46 around the shanks abut against the underside of members 55, 56 hereinafter described which bear against the underside of the head 44, and above the head there are other members 53, 54 and washers 47, 48 which are held down by nuts 50 on the shanks 42, 43, so that the flexplates are rigidly secured to the head. Bushings 51, 52 enter the members 53, 55 which surround shank 42 and members 54, 56 around shank 43. A slight amount of play is left between the shanks 42, 43 and the bushings 51, 52 in the head, through which the shanks pass, and the parts are tightened up after they have been assembled in situ on the machine, so as to ensure that at the dead points of the movement of the head the flexplates 36, 37 are not subject to any bending stress. The stresses produced in the flexplates as the parts move to mid-stroke will, therefore, be equal in each direction of bending.

The reciprocable head 44 is supported so as to move parallel to itself in an up-and-down direction by means of four flexplates which extend from it horizontally. Two of these flexplates 53, 54 are secured rigidly to the upper face of the reciprocable head by the nuts 50 on the shanks 42, 43 as already described, and two flexplates 55, 56 are secured to the lower face. They extend rearwardly from the head 44 into engagement with an anchoring block 57 fixed to the back edge of the foundation block 14. The anchoring block 57 is held down by bolts 58, 59. The upper two flexplates 53, 54 extend parallel to one another, so that the anchoring block 57, the two flexplates 53, 54 and the reciprocating head 44 as viewed in plan form a rectangle. At the ends of the anchoring block, steps are cut out of the metal of the block so as to provide horizontal surfaces 60 at a lower level than those to which the upper flexplates are secured, the difference in level corresponding to the thickness of the reciprocable head 44. The lower flexplates 55, 56 extend horizontally from the head to the upperside of the steps cut in the anchoring block 57. In order to engage these steps, the lower flexplates 55, 56 are splayed so that they form, in conjunction with the upper flexplates, as viewed in plan, a triangulated structure (see Figure 4). As viewed in side elevation, the upper and lower flexplates are, however, in parallel planes (see Figure 2).

The flexplates which support the reciprocable head may be machined from flat bar which is fairly stout in thickness, so as not to be liable to buckle under endwise pressure, but is made thinner for a short distance near its fixing bolts at each end, as at 61, 62, Figure 2, to provide two thin portions which are springy to a sufficient extent to permit the head to be reciprocated up and down by the eccentricities without inducing fatigue stresses in the flexplates.

The flexplates are made of a low-carbon machinable steel, and they do not require to be tempered if they are of suitable dimensions.

Each of the eccentric straps 32, 33 has an eye 63 or 69 below it, and a hooked rod 70 or 71 is engaged with the eye and depends vertically into hooked engagement with the upper end of a strong retaining spring 72 or 73, as the case may be. The other end of each spring is engaged with an eyebolt 74 or 75 in the baseplate 11 of the machine, and the tension of the spring can be adjusted by means of nuts 76, 77 on the screwed shank of the eyebolt. The lower ends of the

5

hooked rods 10, 71 which are engaged with the springs have weights 78, 79 of suitable amount secured thereto. It will be noted that the effect of these springs is to draw the eccentric straps downwardly, and if the springs are made strong enough, this downward force will exceed the upward force which is applied to the underside of the reciprocating head when the tools upon it make impact upon the fastener elements in the operation of the machine, the result being that the direction of the force applied to the eccentric straps and the ball races by the eccentric portions of the shaft is always upwards, the eccentric strap always bearing at the top on the ball race which in turn bears on the top of the eccentric portion of the shaft. Thus even the extremely small play or lost motion which may be present in the ball races is counteracted from affecting the movement of the reciprocable head 44. The effect of the weights 78, 79, on the rods above the springs, if the amount of the weights is properly adjusted relatively to the stiffness of the springs and the speed of operation, is to assist in ensuring this result. The natural period of vibration of the weight and spring must be made not to coincide with the rate of reciprocation of the head.

Upon one side of the foundation block 14 (Fig. 4) is mounted a bracket 80 which supports a ball bearing 81 for a horizontal strip-feed shaft 82. The strip-feed shaft 82 extends across the block 14 behind the reciprocating head 44 and beneath the flexplates 54, 56 which support the head, the axis of the strip-feed shaft being about level with the upper surface of the block 14, which is machined out to receive it. In the center and extending to the rear of the block 14 is a large rectangular opening 83 which is spanned by the strip-feed shaft 82. Here the shaft is supported by two further ball bearings 84, 85 (Figure 6) on a suitable assembly frame 86 inserted into the opening and secured by screws 91, 92.

Between these ball bearings the strip-feed shaft carries serrated feed rolls 87, 88 (Figures 5 and 6) and the strip material 89, 90 which is to be formed into fasteners passes over these feed rolls. Secured to the feed rolls are toothed pinions 93, 94, and above the strip-feed shaft 82, and parallel to it, there is a non-rotatable spindle 95 on the assembly frame which supports further feed rolls 97, 98 carrying pinions 99, 100 which mesh with the pinions 93, 94 on the strip-feed shaft 82. The feed rolls and pinions on the non-rotatable spindle are supported thereon by needle roller bearings 101, and the non-rotatable shaft is pressed firmly down towards the feed shaft by means of two strong springs 102, 103 which bear upon it and are located beneath yokes 104 stopped against nuts on studs 105, 106 on each side of the shaft.

In this way the upper feed rolls are pressed strongly against the upper surface of strip material being fed, and they are also driven, through the pinions 99, 100, in timed relation to the lower feed rolls 87, 88. This is necessary in order to ensure a non-slip drive. The teeth of the pinions 93, 94 and 99, 100 are made sufficiently deep to permit of a slight up-and-down movement of spindle 95 against the springs 102, 103 without becoming unmeshed.

It is also necessary that the non-rotatable spindle 95 which carries the upper feed rolls should be prevented from any movement in a horizontal direction, although up-and-down

6

movement against the springs is permitted. To this end, two flexplates 107, 108 are secured to the spindle 95 at its ends, and they extend horizontally to an anchoring platform 109, lying to the rear of the non-rotatable spindle and secured to the assembly frame 86. This obviates the need which would otherwise exist for guides, and also eliminates the friction associated with such guides. In order to relieve the pressure of the feed rolls when fresh strip is being fed into the machine, two cam levers 110, 111 are mounted on the non-rotatable spindle 95 adjacent to the springs 102, 103. When these levers are moved from normal position, they cam and lift the spindle. When the strip has been inserted, the levers can be returned to their initial position; pressure then is put on the strip in readiness to feed it forward.

The assembly of roller bearings 101 with the upper feed rollers, non-rotatable spindle 95, flexplates 107 and 108, and supporting platform 109 therefor, and springs 102, 103, to urge the non-rotatable spindle downwardly, is conveniently mounted on the assembly frame 86, as a unit assembled on a plate 112 removable from the assembly frame, and so can be separately adjusted or renewed when worn.

On that end of the main driving shaft 24 of the machine which lies on the same side of the foundation block 14 as the aforesaid bracket 80 which supports the end bearing of the strip-feed spindle 82, there is located a ball bearing eccentric 120 surrounded by a strap 121 which is formed in one piece with an eccentric rod 122 carrying a pawl 123. The eccentric rod 122 extends diagonally upwardly and rearwardly from the driving shaft into a position where the pawl 123 is to the rear of, and is slightly underneath, the strip-feed shaft 82. Here the strip-feed shaft carries a ratchet wheel 124 for engagement with the pawl 123. The eccentric rod 122 is prolonged beyond the pawl and enters a fork on the end of a control rod 125, endwise movement of which will serve to pull the pawl out of engagement with the ratchet wheel or, if in the other direction, to push it back into engagement. A spring 126 surrounds the control rod 125 and acts to maintain the pawl in engagement with the ratchet wheel. A brake-collar 127 is mounted on the strip-feed shaft 82 adjacent to the ratchet wheel 124, and a steel brake-block is urged against the underside of collar 127 by a strong spring to prevent reverse rotation. The brake-block slides in bracket 80 and is therefore hidden from view in the drawings but is similar to block 140 hereinafter described.

The control rod 125 is urged by spring 126 in the direction to bring about engagement of the pawl with the ratchet wheel, but is secured to the core of a solenoid 130. When the solenoid is energized, the pawl is drawn out of engagement, and feed of the metal fastener strips 89, 90 ceases.

Above the foundation block 14, and to one side of the reciprocating head 44, on the lefthand side of the machine as viewed from the front, there is secured a base 131 of a stringer-tape feed-bracket 132. The base 131 is secured in place near the edge of the foundation block 14 by a screw 133 which passes through the foundation block from below and which acts as a pivot. It is secured also by a second screw 134 entered from above, and when the second screw is tightened up the bracket is in its working position. If the second screw 134 is undone, however, the bracket can be swung out of the

way, using the first screw as a pivot, to afford easier access to the tools on the reciprocable head 44 and on the foundation block 14 below it. The stringer-tape feed-bracket 132 extends upwardly from its base on the foundation block, and then horizontally across the front of the machine, and at its far end carries a depending portion 135. A stringer-tape feed-shaft 136 extends in a horizontal direction through the bracket below the upper arm thereof, and finds a bearing in the aforesaid depending portion. It also has a bearing in the upwardly extending portion of the bracket above the base 131 thereof. This feed shaft carries a ratchet wheel 137 at the end of the feed shaft which projects beyond the base. The ratchet wheel is operated by an eccentric strap 138 on the driving shaft of the machine, which eccentric strap is formed in one piece with an eccentric rod 139 carrying a pawl 141 for engagement with the ratchet wheel. This pawl and the strap, and a friction brake 140 on the stringer-tape feed-shaft, are similar to the pawl, strap and brake for operating the strip-feed shaft 82, with the exception that no means is provided for rendering the pawl inoperative during operation of the machine. The brake-block 140 has a stem 142 which passes freely through the top of bracket 132 and carries a nut 143. Surrounding the stem, within the bracket 132, is a strong spring which applies 30 brake pressure but the nut permits brake pressure to be relieved when necessary.

Upon the stringer-tape feed-shaft 136, beneath the arm of the bracket 132 which supports it, there are secured two knurled feed wheels 144, 145 around which stringer-tapes can be led, and friction with which causes the tapes to be drawn upwardly through the machine, past the foundation block 14 and the reciprocable head 44. Guides 146 are provided for the tapes below the foundation block 14, and in the head are further guides 147 in addition to the feed wheels 145 on the feed shaft. Above the knurled feed wheels 145 there are spring-pressed friction blocks 148 which press the tape down on to the feed wheels. Each of the friction blocks 148 has a rod 149 which passes upwardly through the arm of the bracket and is connected above the bracket arm with a cam lever 150. A spring 151 surrounds the shank of each bracket and urges it downwardly into engagement with the tape, but operation of either of the cam levers will enable the corresponding friction block 148 to be lifted against the action of the spring. When the operator is threading up stringer-tapes through the machine, he lifts the friction blocks by means of the cam levers, to permit him to position the tapes readily around the knurled wheels. When they have been positioned, the cam levers are thrown over to enable the friction blocks to engage the knurled feed wheels 144, 145, and thereafter, provided the fastener strips 89, 90 are in position between the pairs of fastener-strip feed-wheels 81, 87 and 88, 93, the operation of the machine can begin.

The reciprocable head and the foundation block may be and preferably are constructed in the manner of, and so that they may receive punches and dies such as are described in, the aforesaid Patent No. 2,437,793, and, for certain combinations herein, are considered to be constructed in accordance with that disclosure.

Two sets of punches and dies are provided to correspond to the two stringer-tapes and two fastener strips 89, 90, which the machine is able

5 to feed simultaneously. The punches and dies may be such as to cut a small notch in each side of the strip when severing fasteners, if desired. In this case the punches are provided with flutes which constitute air passages, and the dies have lateral openings for the ejection of scrap. The air blast is made strong enough so that air passing along the flutes will blow out scrap through the lateral openings. Scrap delivery tubes are in this case secured to the outlets of the ejection openings and serve to convey the scrap to a suitable receptacle placed on the base.

Even if the fastener elements are not to be notched, the air blast may be useful in keeping the tools cool.

Thus the machine will secure the fastener elements to two stringer-tapes simultaneously, feeding them upwardly through the machine. When a predetermined number of fastener elements have been secured to a stringer-tape for a determined length for a sliding clasp fastener, the further feed of fastener strip is interrupted by energization of the solenoid, while feed of the stringer-tape is allowed to continue. This results in a length of tape devoid of fastener elements. When the solenoid is released, a further series of fastener elements is secured to the tape. Thus lengths of tape complete with fastener elements alternate with short blank lengths which constitute the ends of the tapes in completed sliding-clasp fasteners.

35 In order to operate the solenoid correctly, a contact (not shown) may be provided on the end of the stringer-tape feed-shaft 82, or some other part of the machine, which contact is actuated at intervals which can be accurately set. The contact can be made to operate a counting apparatus, for example, one of the known electronic counters, so that the solenoid will be caused to be energized only after a specific number of fastener elements has been secured to the tape.

40 It will be observed that in the machine described, all the parts which have to execute a linear movement, and which would normally be constrained by guides, are supported by flex- 45 plates so that the friction involved in the use of guides is done away with. Although the invention has been described in connection with the employment of a machine in which fastener elements are produced by punches from flat strip, it is to be understood that the invention could be used on machines of other known types, such as the known machines for producing fastener elements by shearing them, in a plane parallel to the interengaging faces of the elements, from preformed wire. Also the apparatus is capable of uses, both in the field of slide fastener manufacture and otherwise outside of 50 the process of forming and attaching slide fastener elements to tape.

55 What is claimed as new and useful is:

1. In press construction, a base, a ram, complementary means on the base and the ram for working metal presented between the ram and the base, resilient means for supporting and retaining the ram for reciprocable movement in relation to the base along a fixed substantially rectilinear path, a rotatable shaft, and means for transmitting motion from the shaft to the ram against the action of said last mentioned means, the motion-transmitting means including an eccentric connection to the shaft, a member rigidly secured to the ram and the eccentric connection, and spring means for leading the

eccentric connection so that it will apply stress to the shaft constantly in the same direction.

2. In press construction, a base, a ram, complementary means on the base and the ram for working metal presented between the ram and the base, resilient means for supporting and retaining the ram for reciprocable movement in relation to the base along a fixed substantially rectilinear path, a rotatable shaft, and means for transmitting motion from the shaft to the ram against the action of said last mentioned means, the motion-transmitting means including an eccentric connection to the shaft, a member rigidly secured to the ram and the eccentric connection, and spring means for forcing the eccentric connection against the eccentric constantly in the same direction.

3. In a press construction, a base, a head movable relative to said base, complementary means carried by the base and the head for working material presented therebetween, a plurality of substantially parallel cantilever-like elongated bar-like members having resilient characteristics and having one end thereof rigidly affixed to said base, said head mounted on the opposite free end of said bar-like members and adapted for limited movement in relation to the base along a fixed substantially rectilinear path substantially perpendicular to said bar-like members, and means for effecting reciprocating movement of said head relative to said base against the action of said bar-like members.

4. In a press construction, a base, a head movable relative to said base, complementary means carried by the base and the head for working material presented therebetween, a plurality of substantially parallel cantilever-like elongated bar-like members having resilient characteristics and having one end thereof rigidly affixed to said base, said head mounted on the opposite free end of said bar-like members and adapted for limited movement in relation to the base along a fixed substantially rectilinear path substantially perpendicular to said bar-like members, a rotatable shaft, and means for transmitting motion from the shaft to the head including an eccentric connection arranged with the shaft, and a flexible member connecting said head with said eccentric connection whereby said eccentric connection is adapted to move laterally relative to the connection of said flexible member with said head.

5. In a press construction, a base, a head movable relative to said base, complementary means carried by the base and the head for working material presented therebetween, a plurality of substantially parallel cantilever-like elongated bar-like members having resilient characteristics and having one end thereof rigidly affixed to said base, said head mounted on the opposite free end of said bar-like members and adapted for limited movement in relation to the base along a fixed substantially rectilinear path substantially perpendicular to said bar-like members, a rotatable shaft, at least two connecting rods with each having one end rigidly connected to said head and the opposite end connected to an eccentric connection arranged with said shaft, each of said connecting rods characterized in that they have limited flexure.

6. In a press construction, a base, a head movable relative to said base, complementary means carried by the base and the head for working material presented therebetween, a plurality of substantially parallel cantilever-like

elongated bar-like members having resilient characteristics and having one end thereof rigidly affixed to said base, said head mounted on the opposite free end of said bar-like members and adapted for limited movement in relation to the base along a fixed substantially rectilinear path substantially perpendicular to said bar-like members, a rotatable shaft, means for transmitting motion from the shaft to the head including an eccentric connection arranged with the shaft, a member rigidly secured to the head and the eccentric connection and characterized in that it has limited flexure, and spring means for forcing the eccentric of the eccentric connection constantly in the same direction.

7. In a press construction, a base, a ram, complementary means on the base and ram for working metal presented between the ram and the base, resilient means for supporting said ram for reciprocable movement in substantially a fixed rectilinear path relative to said base, a rotatable shaft, means for transmitting motion from the shaft to said ram against the action of said supporting means, the motion-transmitting means including an eccentric portion carried by said shaft, an eccentric strap disposed around said eccentric portion, a member rigidly secured to the ram and said eccentric strap, and spring means for pulling the eccentric strap against said eccentric portion of said shaft constantly in the same direction.

8. In a press construction, the combination defined in claim 7, whereas the means supporting the ram for reciprocable movement in substantially a fixed rectilinear path relative to the base, includes a plurality of bar-like members having resilient characteristics with one end of each of said bar-like members rigidly secured to said base with the ram secured to the opposite free ends thereof.

9. In a press construction, a base, a reciprocable head, complementary material-working members carried by the base and head for forming material presented therebetween, a plurality of elongated bar-like members, one end of each of said bar-like members securely affixed to said base with said head being supported and suspended from the opposite free end of said members free of any guideways, a rotatable shaft positioned opposite said head, means for transmitting motion from said shaft to said head against the action of said bar-like members along a fixed substantially rectilinear path, the motion-transmitting means including an eccentric portion carried by said shaft, an eccentric strap disposed around said eccentric portion, a connecting rod having one end secured to said head and the opposite end to said eccentric strap, and spring means for loading the eccentric strap so that it will bear upon the eccentric portion constantly in the same direction.

10. In a press construction, the combination as defined in claim 9, wherein the connecting rod has an intermediate flexible portion whereby that end of the rod connected to the eccentric strap is adapted to move laterally when the shaft is rotated relative to the opposite end of said rod which is securely connected to the head.

11. In a press construction, a base, a head movable relative to said base, the base and head having complementary metal working members carried thereby, elongated means having resilient characteristics for supporting the head free of any guideways in a suspended position for reciprocable movement relative to said base in sub-

stantially a fixed rectilinear path, means connected to said head for producing limited movement of said head relative to said base against the action of said resilient means, a rotatable shaft, an eccentric connection on said shaft, a connecting rod extending between and secured to said head and said eccentric connection, and spring means for loading the eccentric connection so that it will apply stress to the shaft constantly in the same direction.

SONNTAG, ALFRED.
